Primary Examiner—Alan P. Douglas*Assistant Examiner*—Lavone D. Tabor*Attorney, Agent, or Firm*—Richard B. O'Planick[57]*CLAIM

The ornamental design for a broom shroud, as shown and described.

DESCRIPTION

FIG. 1 is a top left front perspective view of a broom shroud showing my new design;

FIG. 2 is a front elevational view thereof; the rear elevational view being a mirror image

FIG. 3 is a top plan view thereof;

FIG. 4 is a left side elevational view thereof;

FIG. 5 is a right side elevational view thereof; and,

FIG. 6 is a bottom plan view thereof.

The broken line showing of bristles in FIG. 1 is for illustrative purposes only and forms no part of the claimed design.
